(57) **CLAIM**

The ornamental design for a guide member for guiding longitudinal flexible members around a wheel, as shown and described.

DESCRIPTION

FIG. 1 is a perspective view of a guide member in accordance with an embodiment of the present design;

FIG. 2 is a right side view of the guide member of FIG. 1; FIG. 3 is a left side view of the guide member of FIG. 1; FIG. 4 is a top view of the guide member of FIG. 1; FIG. 5 is a bottom view of the guide member of FIG. 1; FIG. 6 is a front view of the guide member of FIG. 1; FIG. 7 is a rear view of the guide member of FIG. 1; and, FIG. 8 is a perspective view of the guide member of FIG. 1, shown reduced in scale, illustrating a wheel (shown in broken lines) received by the guide member.

The broken lines represent environment and forms no part of the claim.
